UNITED STATES PATENT OFFICE.

LEO H. TAFFEE, OF HASTINGS, MICHIGAN, ASSIGNOR OF ONE-HALF TO ABEN E. JOHNSON, OF HASTINGS, MICHIGAN.

PUMPING-JACK.

1,334,328.

Specification of Letters Patent. Patented Mar. 23, 1920.

Application filed September 30, 1919. Serial No. 327,544.

To all whom it may concern:

Be it known that I, LEO H. TAFFEE, a citizen of the United States, residing at Hastings, county of Barry, and State of Michigan, have invented certain new and useful improvements in Pumping-Jacks, of which the following is a specification.

This invention relates to improvements in pumping jacks.

10 The main objects of this invention are:

First, to provide an improved pumping jack adapted to be mounted for support on a pump body which is quite compact and of comparatively light weight and easily mounted and connected to the pump rod.

Second, to provide an improved pumping jack in which the moving parts are so supported and arranged that the strain thereon is minimized.

20 Third, to provide an improved pumping jack which is simple and economical in its parts and one which is very durable in use.

Further objects, and objects relating to structural details, will definitely appear 25 from the detailed description to follow.

I accomplish the objects of my invention by the devices and means described in the following specification. The invention is clearly defined and pointed out in the claims.

30 A structure which is a preferred embodiment of my invention is clearly illustrated in the accompanying drawing forming a part of this specification, in which:

Figure I is a front elevation of a pumping jack embodying the features of my invention, a portion of the casing being broken away.

Fig. II is an elevation looking from the right of Fig. I.

40 Fig. III is a detail horizontal section on a line corresponding to line 3—3 of Fig. I showing details of connection for the pitman to the pump rod.

Fig. IV is an enlarged detail partially in 45 vertical section on a line corresponding to line 4—4 of Figs. I, V and VI.

Fig. V is a detail vertical section on a line corresponding to line 5—5 of Figs. II, IV and VI.

50 Fig. VI is a detail horizontal section on a line corresponding to line 6—6 of Figs. II, IV, V and VI.

In the drawing similar reference characters refer to similar parts throughout the 55 several views, and the sectional views are

taken looking in the direction of the little arrows at the ends of the section lines.

Referring to the drawing, 1 represents the body of a pump and 2 the pump rod. The details of the pump are not important and 60 I show the pump herein for the purpose of illustrating an application or adaptation of my improvements.

I provide a casing consisting of a flat outer wall 3 having peripheral flanges 4 at 65 its edges to which the inner wall 5 is secured by the screws 6 and bolts 7. The bolts 7 also secure the supporting brackets 8 which have seats 9 therein for the body of the pump. Clamping yokes 10 embracing the opposite sides of the pump body are secured to the brackets by means of the bolts 11. The casing is thus mounted directly upon and supported by the pump.

The driving shaft 12 is mounted in a 75 bearing 13 on the front wall 3 of the casing. In the structure illustrated, a driving pulley is provided for the shaft 12. On the inner end of the driving shaft is a driving pinion 15.

The pitman 16 is connected to the pump rod 2 by the arm 17, the pitman being provided with a series of holes 18 so that the arm may be located as required for various sizes and makes of pumps. The pitman 85 has direct connection to the pump rod.

The pitman is provided with a rack coacting with the driving pinion comprising a series of rack pins 19 provided with rollers 20. On the inner ends of the pins 19 is a 90 bar 21 which serves the double purpose of a connecting and supporting bar for the pins and an inner guide member coacting with the guide roller 22 on the shaft 12.

An outer yoke guide member 23 is secured 95 to the pitman at 24 to coact with the roller 22, the yoke and the bar guide member described, guiding the movement of the pitman as it is reciprocated by the pinion coacting with the rack. These guide members 100 relieve the pinion and rack of wear.

The outer wall 3 of the casing is adapted as a guide way for the guide yoke 23 while the inner wall 5 is adapted as a guide way for the pitman.

105 A cross guide 25 engages the inner side of the yoke, further supporting the same.

By thus forming and arranging the parts, I secure a pumping jack which is very compact in structure and one which may be made 110

of comparatively light materials and is at the same time very strong and durable. It is readily adaptable to different makes of pumps, and the parts are simple and economical to produce and assemble.

I have illustrated and described my improvements in an adaptation which I find very satisfactory. I have not attempted to illustrate or describe certain modifications and adaptations as I believe the disclosure made will enable those skilled in the art to which my invention relates to embody or adapt the same as may be desired.

Having thus described my invention, what I claim as new and desire to secure by Letters Patent, is:

1. In a pumping jack, the combination of a casing having flat inner and outer walls adapted as guide ways, a driving shaft mounted on the outer wall, a driving pinion on said shaft, a pitman having a series of rack pins on its outer side provided with rollers constituting a rack coacting with said pinion, an inner bar-like guide member mounted on the outer ends of said rack pins, a guide yoke mounted on said pitman to embrace said shaft, a roller on said shaft coacting with said guide yoke and said inner guide member, the outer wall of the casing constituting a guide way for said guide yoke and the inner wall a guide way for said pitman, and a transversely disposed supporting bar mounted in said casing to support the inner side of said guide yoke.

2. In a pumping jack, the combination of a casing, a driving shaft, a driving pinion on said shaft, a pitman having a series of rack pins on its outer side provided with rollers constituting a rack coacting with said pinion, an inner bar-like guide member mounted on the outer ends of said rack pins, a guide yoke mounted on said pitman to embrace said shaft, a roller on said shaft coacting with said guide yoke and said inner guide member, and a transversely disposed supporting bar mounted in said casing to engage the inner side of said guide yoke.

3. In a pumping jack, the combination of a casing having flat inner and outer walls adapted as guide ways, a driving shaft mounted on the outer wall, a driving pinion on said shaft, a pitman having a series of rack pins on its outer side provided with rollers constituting a rack coacting with said pinion, an inner bar-like guide member mounted on the outer ends of said rack pins, a guide yoke mounted on said pitman to embrace said shaft, a roller on said shaft

coacting with said guide yoke and said inner guide member, the outer wall of the casing constituting a guide way for said guide yoke and the inner wall a guide way for said pitman.

4. In a pumping jack, the combination of a casing, a driving shaft mounted on the outer wall, a driving pinion on the inner end of said shaft, a pitman having a series of rack pins on its outer side provided with rollers constituting a rack coacting with said pinion, an inner bar-like guide member mounted on the outer ends of said rack pins, a guide yoke mounted on said pitman to embrace said shaft, a roller on said shaft coacting with said guide yoke and said inner guide member, the outer wall of the casing constituting a guide way for said guide yoke and a transversely disposed supporting bar mounted in said casing to support the inner side of said guide yoke.

5. In a pumping jack, the combination of a casing adapted to be mounted on the pump body and having flat inner and outer walls adapted as guide ways, a driving shaft mounted on the outer wall, a driving pinion on said shaft, a pitman, a rack on said pitman coacting with said pinion, an inner bar-like guide member on said rack, a guide yoke mounted on said pitman, a roller on said shaft coacting with said guide yoke and said inner guide member, the outer wall of the casing constituting a guide way for said guide yoke and the inner wall a guide way for said pitman, and a transversely disposed supporting bar to engage the inner side of said guide yoke.

6. In a pumping jack, the combination of a casing adapted to be mounted on the pump body, a driving shaft mounted on the outer wall, a driving pinion on said shaft, a pitman, a rack on said pitman, an inner bar-like guide member on said rack, a guide yoke mounted on said pitman, a roller on said shaft coacting with said guide yoke and said inner guide member, the outer wall of the casing constituting a guide way for said guide yoke, and a transversely disposed supporting bar to engage the inner side of said guide yoke.

In witness whereof I have hereunto set my hand and seal in the presence of two witnesses.

LEO H. TAFFEE. [L.S.]
